US0D1024804S

(12) **United States Design Patent** (10) Patent No.: **US D1,024,804 S**
(45) Date of Patent: ** Apr. 30, 2024

(54) **WATCH**

(71) Applicant: **HUAWEI TECHNOLOGIES CO., LTD.**, Guangdong (CN)

(72) Inventors: **Chien Wei Tang**, Shenzhen (CN); **Ning Yang**, Shenzhen (CN); **Xiang Yuan**, Shenzhen (CN)

(73) Assignee: **HUAWEI TECHNOLOGIES CO., LTD.**, Shenzhen (CN)

(**) Term: **15 Years**

(21) Appl. No.: **29/815,704**

(22) Filed: **Nov. 16, 2021**

(30) **Foreign Application Priority Data**

May 17, 2021 (CN) 202130293799.9

(51) LOC (14) Cl. **10-02**

(52) U.S. Cl. **D10/32**; D10/30; D10/31; D10/38; D14/344

(58) **Field of Classification Search**

USPC ..... D10/30-31, 32, 37, 38-39, 52-53, 65, D10/70, 78, 98, 127-128, 131-132; D11/2, 3, 4, 5, 7; D14/138 R, 203.5, D14/247, 344, 346-347, 440; D24/167, D24/168; D13/173-177

CLAIM

The ornamental design for a watch, as shown and described.

DESCRIPTION

FIG. 1 is a front perspective view of a first embodiment of a watch, showing our new design; FIG. 2 is a front view thereof; FIG. 3 is a back view thereof; FIG. 4 is a top view thereof; FIG. 5 is a bottom view thereof; FIG. 6 is a right side view thereof; FIG. 7 is a left side view thereof; FIG. 8 is a front perspective view of a second embodiment of a watch, showing our new design; FIG. 9 is a front view thereof; FIG. 10 is a back view thereof; FIG. 11 is a top view thereof; FIG. 12 is a bottom view thereof; FIG. 13 is a right side view thereof; FIG. 14 is a left side view thereof; FIG. 15 is a front perspective view of a third embodiment of a watch, showing our new design; FIG. 16 is a front view thereof; FIG. 17 is a back view thereof; FIG. 18 is a top view thereof; FIG. 19 is a bottom view thereof; FIG. 20 is a right side view thereof; and, FIG. 21 is a left side view thereof. The broken lines in the drawings illustrate portions of the watch and form no part of the claimed design. The oblique line shading in the drawings shows a transparent, translucent and highly polished or reflective surface.
